UNITED STATES PATENT OFFICE.

ALBERT J. MEIER, OF GLENDALE, MISSOURI, ASSIGNOR TO UNIT CONSTRUCTION COMPANY, OF ST. LOUIS, MISSOURI, A CORPORATION OF DELAWARE.

CONCRETE CONSTRUCTION.

1,031,079.

Specification of Letters Patent.

Patented July 2, 1912.

Original application filed November 16, 1909, Serial No. 528,272. Divided and this application filed June 5, 1911. Serial No. 631,286.

To all whom it may concern:

Be it known that I, ALBERT J. MEIER, a citizen of the United States, residing at Glendale, in the county of St. Louis and State of Missouri, have invented certain new and useful Improvements in Concrete Construction, (Divisional Case C,) of which the following is a specification.

This application is a division and continuation of one filed by me November 16, 1909, Serial No. 528,272.

This invention relates to certain new and useful improvements in concrete construction, and pertains more particularly to a construction in which concrete beams and slabs, which form the floor and ceiling, are supported by uprights or columns, and are united integrally together to form a rigid unitary structure.

It is the object of this invention to provide a concrete structure in which reinforcing bars are embedded in, and project from, adjoining oppositely disposed beams and slabs, the projecting ends of the oppositely disposed bars being integrally connected or united to form continuous one-piece bars of double thickness at the points of juncture of the same.

In the drawings, Figure 1, is a view in perspective of the present invention, parts being broken away and shown in section, Fig. 2, is a top plan view, and Fig. 3, is a section taken on the line 3--3 of Fig. 2.

A pair of beams 1 are arranged opposite to each other, and have their ends in abutting engagement and supported from a column 2. Each of the beams is provided with a tenon 4, which terminates in spaced relation to the beam's end, and with a pair of shoulders 3, located on opposite sides of the tenon and below the plane of the latter. A gusset 5, or a plurality of such gussets are formed on column 2. Each gusset 5 is provided with a cut-away portion 6 which communicates with a slot 7 in the end of beam 1.

A reinforcing bar 8 having its ends embedded in the column projects from the column into slots 7 provided in the beams 1, the bar 8 being bowed or arched, in a manner depicted in the drawings. Each tenon 4 is provided with a reinforcing bar or bars 9, which project from each end thereof. Each bar 9 projecting from the end of one of said tenons overlaps an end of a similar

bar projecting from the other tenon, and the overlapping ends of the bars are welded or brazed together electrically or in any other approved and suitable manner, whereby the bars are united securely together and form a continuous bar. Reinforcing bars 10 are embedded in the lower part of each of the beams, and, adjacent the ends thereof, one or more of said bars 10 turn upwardly and project from the beams. The projecting ends of the bars 10, overlap, and the overlapping bar ends are rigidly secured together by welding or brazing. Each cut-away portion 6 is covered by a so-called form (not shown in the drawings) and the slots and cut-away portions are filled with 70 grout or wet-concrete, which is allowed to set therein and unites the beams and the column integrally together.

A flange 11 of each slab 12 rests on a shoulder 3 of a beam 1 and against tenon 4. The flanges 11 raise the top faces of slabs 12 above shoulder 3, so that, when a slab is placed upon each shoulder 3 of a beam 1, a space 13 above the tenon is left between the two slabs supported by the beam. Reinforcing bars 14 are embedded in the slabs 12 and those bars 14, which extend at an angle to space 13, project from each slab into said space. Each bar 14 projecting from one of said slabs into space 13 overlaps a similar bar 14 projecting from an adjacent slab, and said overlapping bars are secured together by welding or brazing, whereby the bars are made continuous and the slabs are firmly and securely connected 90 together. Grout or wet-concrete 15 is poured into space 13, and, when it sets therein, unites the slabs and the beams to form a unitary structure.

From the above it will be seen that the integral connections between the reinforcing bars 14 of the slabs provide continuous rods with portions of double thickness, which latter overlie the beams 1. Further the reinforcing rods 9 of the tenons have similar portions of double thickness which overlie the column. The connections between the several concrete elements are thus not only of great effectiveness, but, in addition, the parts are reinforced and strengthened at the points where the greatest stresses exist.

What is claimed is:

1. In concrete construction, a column,

- pair of beams having their inner ends resting on said column, slabs supported on the beams and having their opposite sides adjacent the column arranged in spaced relation,
- 5 which space overlies the column, a series of reinforcing bars carried by each beam and projecting into said space over the column, the ends of the opposing bars overlapping each other and being integrally connected
- 10 to form portions of double thickness which overlie the column, and a series of bars carried by the opposing slabs and projecting in said space over the column, the ends of opposing bars of said slabs overlapping each other and being integrally connected to form portions of double thickness that overlie the column and project in said space thereabove and cross said portions of double thickness of the bars of the beams at points over the column.
- 15 2. In concrete construction, a column, a pair of beams having their inner ends resting on the column, a tenon on each beam, shoulders on opposite sides of the
- 20 tenons of the beams, slabs seating on the shoulders and abutting the tenons and hav-
- ing their top faces extending above the top faces of the beams and providing a space between their opposite sides which space overlies the column, a series of reinforcing bars carried by each beam and projecting into said space over the column, the ends of the opposing bars overlapping each other and being integrally connected to form portions of double thickness which overlie the column, and a series of bars carried by the opposing slabs and projecting in said space over the column, the ends of opposing bars of said slabs overlapping each other and being integrally connected to form portions of double thickness that overlie the column and project in said space thereabove and cross said portions of double thickness of the bars of the beams at points over the column.
